UNITED STATES PATENT OFFICE.

GEORGE S. HILL, OF HAVERHILL, MASSACHUSETTS, ASSIGNOR, BY MESNE ASSIGNMENTS, TO THE SINGER MANUFACTURING COMPANY, A CORPORATION OF NEW JERSEY.

CUTTING ATTACHMENT FOR SEWING-MACHINES.

SPECIFICATION forming part of Letters Patent No. 703,960, dated July 1, 1902.

Application filed January 19, 1899. Serial No. 702,629. (No model.)

To all whom it may concern:

Be it known that I, GEORGE S. HILL, of Haverhill, in the county of Essex and State of Massachusetts, have invented certain new and useful Improvements in Cutting Attachments for Sewing-Machines, of which the following is a specification.

This invention has relation to that class of machines for forming a series of groups of 10 stitches, such as cross-bars, the said class of machines being exemplified by my Patent No. 548,877, dated October 29, 1895, to which reference is to be had for the understanding of the main features of the machine hereinafter 15 described.

The objects of the invention are to provide for the automatic cutting of the upper and under threads of the stitch-forming mechanism at points beneath the work, to provide 20 for the loosening and drawing out of the threads prior to said cutting in order that they may properly interlock when the operation of sewing the next cross-bar is begun, to provide for the actuating of the cutting devices by automatically-operating means, to 25 provide for the automatic locking of the upper thread during and after the cutting of the same and for the withdrawal of its severed end after it has been cut, and to provide 30 for the locking of the cutting, loosening, and clamping mechanism out of the way when the needle is being actuated to sew the cross-bars.

To these ends the invention consists of the improvements which I shall now proceed to 35 describe in detail and then point out in the claims hereto annexed.

Reference is to be had to the accompanying drawings, and to the letters and figures marked thereon, forming a part of this specification, similar characters indicating similar parts or features, as the case may be, wherever they occur.

Of the drawings, Figure 1 is a side elevation of a sewing-machine with the casing removed, equipped with my improvements. Fig. 2 is a front end elevation of the same, showing the parts in their respective positions just after the threads have been cut and the operation of sewing the cross-bar has been

completed. Fig. 3 is a similar view illustrating the positions of the respective parts immediately prior to the operation of cutting the threads. Fig. 4 is an elevation from the rear end when the parts are in their respective positions shown in Fig. 2. Fig. 5 is a vertical section on the line 5 5 of Fig. 1 with the parts in their respective positions illustrated in Fig. 4. Fig. 6 is a similar section on the said line, but illustrating the parts in the positions they assume prior to the cutting 60 of the threads. Fig. 7 is a bottom view of the machine looking from beneath. Fig. 8 shows the position of the cutting-blade prior to the cutting of the threads. Fig. 9 shows the same immediately after the under thread 65 has been cut. Fig. 10 also shows the same after both threads have been cut. Figs. 11 and 12 illustrate the adjustable cam and the pulleys on the needle-bar-driving shaft. Fig. 12^a represents a section on the line 12^a 12^a, 70 Fig. 11. Fig. 13 is an enlarged section of the devices for loosening the upper thread. Fig. 14 illustrates the hand-operative device and its coöperating and adjacent parts for bringing the cutting devices into operation. Figs. 75 15 and 16 illustrate in enlarged views the mechanism for loosening or drawing out the under thread prior to its being severed. Fig. 17 shows the device for locking the upper 80 thread to the needle-bar. Figs. 18 and 19 illustrate the loosening mechanism for the upper thread. Fig. 20 is a perspective view of the stationary and the movable blades for severing the threads.

My invention, as has been hereinbefore 85 stated, is especially applicable to that class of machines typified by my Patent No. 548,877, dated October 29, 1895, and as many of the main parts of the machine shown in the accompanying drawings are illustrated and described 90 therein I shall not attempt to again describe them, as a perfect understanding thereof may be gained from the said patent.

The machine is provided with a bed-plate 95 a, upon which are mounted the supports and bearings for the operative parts thereof, those movable parts beneath the plate being inclosed within a casing, as partially illustrated

in Figs. 2, 3, and 6. The plate is hinged to the casing at the back by pintles *b*, extending through lugs *c* thereon.

d is the continuously-rotating driving-shaft, 5 which is mounted in bearings at the back of the plate, substantially in alignment with the pintles *b*, so that the bed-plate may be swung up to expose the operative parts on the under side thereof without removing the driving-shaft from the pulley *e* on the driving-shaft. 10 Power may be imparted to the belt for rotating the pulley in any suitable way.

On the needle-bar-driving shaft *f*, Fig. 11, are mounted a loose pulley *b'* and a fast pulley *c'*, with either of which a belt extending from a pulley *g* on the driving-shaft may engage, being shifted from one to the other by a belt-shifter *h*, the operation of which will be hereinafter described.

20 On the end of the standard is mounted a vertically-reciprocating needle-bar operated by suitable mechanism interposed between it and the driving-shaft *f* and coacting with a thread-carrying looper or shuttle beneath 25 the bed-plate for interlocking the threads through a fabric; but as these parts are not of the present invention I shall not describe them.

The upper needle, with the devices that operate it, I term the "upper-thread mechanism," and the looper, the shuttle, the under needle, or other form of device for the under thread, with its driving or operating devices, I term the "under-thread mechanism," and I 35 term the thread 5, carried by the upper-thread mechanism, either the "needle-thread" or the "upper thread," while I term the other thread 4 the "under thread" or the "looper-thread."

Mounted in bearings on the under side of 40 the bed-plate is a longitudinal rock-shaft *i*, by means of which power is imparted to the devices which I shall now describe for drawing out and loosening the upper and the under threads, cutting the latter at the proper 45 time, and then freeing the severed end of the upper thread.

The shaft *i* is provided with a collar *j*, rigid thereon, to which a lever *k* is hinged by a vertical pivot. The free end of the lever is provided with an antifriction-roller *l*, which is adapted to be moved into and out of engagement with a cam *m* on a stud-shaft *n*. The driving-shaft *d* is provided with a pinion *o*, engaging and driving a gear-wheel *p* on the 55 shaft *n*, so that the cam *m* is continuously revolved. For engaging and disengaging the roller *l* with and from the cam *m* I employ an inclined hand-operative rod *q*, extending up through the bed-plate *a* and provided with a 60 button or key *r* to be pressed by the fingers. The lever *k* is normally disengaged from the cam, but may be easily moved laterally and downwardly into engagement therewith by depressing the finger-piece or button *r*.

65 The projecting end of the shaft *i* is provided with a slotted arm *s*, extending into a slot in

the lower end of a bar *t* and engaging a pin *u* thereon. The bar is adapted to reciprocate through an externally-threaded sleeve *v*, vertically adjustable in a lug *w*, extending from 75 the side of the standard, and in a guide *x*, also extending out from the side of the standard. The bar is provided with a clip *y*, between which and the adjustable sleeve and around the bar is placed a coiled tension-spring *z*. The tension of the spring is adjusted or varied by adjusting the threaded sleeve *v* in its internally-threaded supporting-lug. The upper end of the bar *t* is adapted to press against a cam *a'* on the shaft *f* and 80 secured to the fixed pulley *c'*. The cam is provided with a curvilinear slot through which extends a bolt *d'*, having its end secured to a plate *e'*, fastened to the fixed pulley by screws, so that the cam may be adjusted relatively to 85 the fixed wheel and secured in the desired adjustment by a nut *f'* on the bolt *d'*. The face of the fixed pulley opposite to the cam is provided with a groove through which the bolt *d'* extends, and in the said groove and on 90 either side of the bolt I place cushioning-springs *g'*, the plate *e'* having slots through which its fastening-screws pass to permit of a slight movement of the fixed pulley in either direction relatively to the cam. The cam is 95 provided with a recess *h'*, into which the end of the bar *t* may enter to stop the rotation of the needle-bar-driving shaft *f*. It will be observed that the cam is provided with three 100 dwells 1, 2, and 3, those at 1 and 2 being separated by a relatively steep shoulder and those at 2 and 3 being separated by a slight shoulder. The dwells 1 and 3 are separated by the notch *h'*, and the dwell at 2 is practically a 105 semicircle.

The belt-shifter *h*, which I have hereinbefore referred to, is mounted on the end of a support *i'*, extending out from the standard, and is provided with an arm having a curved slot *j'*, into which extends a pin *k'* from the 110 bar *t*. When the bar is at its lowest point, the belt will be on the fast pulley; but as it rises the belt will be shifted to the loose pulley, as will be clearly understood. The bar is normally locked against movement and held 115 away from engagement with the cam by means of the following devices:

l' is an arm extending inward from the rock-shaft *i* and pivoted at its end to one of a pair of toggle-levers *m'*. When the levers *m'* are 120 in the position illustrated in Fig. 6, the bar *t* is held away from the cam *a'*, and when they are at an angle to each other, as shown in Fig. 5, the tension of the spring *z* will force the end of the bar up into engagement with the cam. A spring *n'* and a weight on the end of the arm *l'* tend to hold the toggle-levers in their locked position. When it is desired to lock the toggles, the key or push-button *r* is depressed and the roller *l* is moved into engagement with the continuously-revolving cam *m*. 125 The latter depresses the lever *k*, and thereby 130

rocks the shaft, draws down the arm s far enough to free the end of the rod t from the notch h' , and then to move the belt-shifter to cause it to throw the belt on the fast pulley 5 c' . The spring n' and the weight on the end of the arm l' assist the cam m in throwing the toggle-levers into their locked position. For unlocking them an automatically-acting device is provided, consisting of a wiper s^2 , mounted on a horizontally-revolving cam-disk t^2 , keyed on a shaft u^2 , which is geared by wheels (not shown) with the needle-bar-driving shaft f . The parts are so timed during the forming of the last stitch that the 10 wiper will engage one of the toggle-levers m' , throwing the latter out of their locked positions, thus allowing the shaft i to rock and the bar t to become again engaged with the cam a' . 15

20 I shall now proceed to describe the devices for drawing out and loosening the under thread and the upper thread and the means for severing them beneath the bed-plate. o' is the lower clamp, suitably mounted 25 above the throat-plate to extend beneath the needle, and has pivoted to its outer end an elbow-lever p' . To the upper end of the short arm of the said lever p' I secure an upper clamp q' , between the end of which and 30 the lower clamp o' the work may be firmly held to be guided to the needle. A flat curved spring r' tends to hold the clamp-plate q' in its raised position, as illustrated in Fig. 2. 35

s' is a kicker pivoted to the forward part of the standard and is provided with a bent finger t' , which extends into engagement with the needle-thread, so as to draw the severed end thereof out of the fabric. It is reciprocated by a link u' , rigidly secured to the top 40 of the short vertical arm of the lever p' . v' is a pin having a head and passed through an eye w' in the end of the long arm of the lever p' and being adapted to slightly reciprocate vertically in guide x' under the bed-plate. 45

y' is one of a pair of toggle-levers which is pivoted at one end to the guide x' and at the other end to the other toggle-lever z' . This last said lever z' is pivoted in the end of the 50 vertically-movable pin v' and is provided with a laterally-extending arm a^2 . The spring r' tends to normally hold the upper clamp q' raised and the pin v' in its uppermost position; but when the toggle-levers are straightened, as illustrated in Fig. 3, the pin v' is drawn down and the clamp-plate q' is forced to its clamping position. The toggle-lever z' is provided with another arm b^2 , by means of which the levers may be moved from their 55 locked positions. To move the levers into and out of their locked positions, I adjustably secure an arm c^2 by a set-screw c^{51} rigidly to the rock-shaft i (thus constituting an automatically-operative device) and provide it 60 with an antifriction-roller d^2 , which is adapted to strike and bear against the arms a^2 and b^2 , respectively, as it is being reciprocated.

When the toggle-levers m' , before referred to, are unlocked and the rock-shaft i is being rocked up, the arm c^2 will move the greater portion of its throw before it strikes the arm b^2 of the toggle-lever z' to release the toggle-levers y' and z' from their locked position, and the spring r' will then draw up the pin v' and raise the upper clamp q' . 70

Pivoted on the shuttle-box is a lever f^2 , having a pull-off g^2 , which is adapted to engage the under thread prior to its being severed and draw out a sufficient length of it for the forming of a first stitch at the beginning of 80 the next operation. The lever f^2 is provided with a slot h^2 of the shape shown in Figs. 15 and 16—that is to say, the slot is divided into three portions, the two outer portions being vertical and connected by the inclined middle portion. The pin i^2 extends from the arm c^2 into the said slot. 85

The device for cutting the threads is located beneath the work and the bed-plate. It consists of a stationary plate j^2 with a rigid ledger-plate k^2 and a plate l^2 , movable in guides m^2 m^2 underneath the bed-plate, and having a blade n^2 , provided with two cutting edges o^2 and p^2 , separated by a shoulder, the first being for the upper thread and the other for 90 the under thread. The edges of the blades n^2 and k^2 are at an oblique angle to each other, so that when the plate l^2 is moved the blades o^2 and k^2 will first sever the upper thread and after a predetermined period of time sever the 95 under thread. The plate l^2 is reciprocated by means of an arm q^2 , secured adjustably on the rock-shaft i by a set-screw q^{51} and having in its end a pin extending into an eye r^2 on the 100 under side of the plate l^2 . 105

I shall now describe the devices for locking the upper thread to insure that the kicker s' , before described, shall draw out of the fabric the severed end thereof.

v^2 is a horizontal rock-shaft extending from the standard below the gooseneck to the forward part thereof. Its rear end is provided with an arm w^2 , by means of which it is given a slight rocking motion as the bar t enters the notch h' in the cam a' . To the end of the 115 arm w^2 is pivoted a link x^2 , having at its lower end a slot y^2 , into which extends a pin z^2 from the arm l' , before described as being rigidly secured to the rock-shaft i . At its forward end the rock-shaft v^2 is provided with 120 a wedging or locking lever a^3 . The parts are so timed that the needle-bar is in its uppermost position when the wedging-lever a^3 is rocking forward. The needle-bar is provided with a head c^3 , secured thereto by a set-screw 125 d^3 . (See Fig. 17.) The said head c^3 is provided near its edge with a slot e^3 , through which the upper thread passes, so that when the wedging-lever a^3 is rocked forward it presses against the spring-strip f^3 in the head 130 formed by the slot e^3 and tightly wedges or locks the thread in the slot. The thread passes from the spool g^3 , through the guide h^3 , under a spring-held friction-plate i^3 , through

the eye j^3 , from thence through a slotted guide k^3 , up to and through an aperture in the end of the take-up b^3 , down to a guide m^3 , through the said slot e^3 , to and through the eye of the 5 needle. The rock-shaft v^2 is utilized to operate a thread pull-off n^3 , as well as to loosen the friction-plate i^3 . The thread pull-off n^3 is also mounted on the end of the rock-shaft v^2 and plays in the slotted guide k^3 . To provide for this pulling off the thread, the friction-plate i^3 is loosened. An arm o^3 is mounted on the rock-shaft and is arranged to press out a pin p^3 when the shaft v^2 is rocked to thrust out the friction-disk i^3 and release it 10 from engagement with the thread, so that the latter may be drawn from the spool without friction. The friction-disk i^3 is mounted on a stud q^3 , and the pressure of the spring r^3 thereagainst is regulated by a nut s^3 . The 15 arm c^2 is adjustably secured upon the shaft i by the set-screw c^{51} , whereby the movements of the kicker, the clamp, and the pull-off g^2 may be varied, as desired, the arm q^2 being likewise adjustable on said shaft by the set- 20 screw g^{51} to vary the movements of the knife or cutter.

Having thus described the various parts of my improvements, I will now proceed to set forth the operation of the same.

30 Let it be supposed that one operation of sewing a cross-bar has been entirely completed and the work has been removed from the clamps q' and o' . The parts are then in the positions illustrated in Figs. 1, 2, 4, 5, 35 and 10. The work is placed between the clamps o' and q' , and the push-button or key r is depressed. This throws the roller l laterally under the cam m , and the rock-shaft i as the cam revolves draws down upon the 40 bar t to free it from the cam a' , and the toggle-levers $m' m'$ lock it in its lowermost position. The parts are then in the positions illustrated in Figs. 3, 6, 8, and 16—that is to say, when the bar t was depressed it operated the belt-shifter to throw the belt from the loose pulley to the fast pulley, so that the needle-bar-driving shaft f is being rotated. The shaft f then operates the needle-bar and the shuttle by means not described, 50 and also begins to rotate the shaft u^2 and the wiper-cam t^2 . While the bar t is held by the toggle-levers m' away from the cam a' the needle and the shuttle are actuated until the wiper s^2 on the cam t^2 strikes against one of 55 the toggle-levers m' and throws them from their locked position. The parts are so timed that as the rock-shaft is unlocked the bar t comes under the tension of the spring z just as the cam a' presents the edge of the dwell 60 3 next to the notch h' thereto. Then as the cam a' revolves it allows the spring to force the bar upward until it enters the notch h' . As the bar rises it throws the belt-shifter to one side to shift the belt from the fast to the 65 loose pulley. As the shaft i is rocked for the first part of the movement the arm l' rises without affecting the link x^2 and the rock- 70

shaft v^2 . The arm c^2 in rising carries the pin i^2 in the lower vertical portion of the slot h^2 without affecting the under thread pull-off g^2 ; but as the rock-shaft i traverses the second part of its movement the arm c^2 in rising carries the pin i^2 through the intermediate portion of the slot h^2 of the lever f^2 . This moves the pull-off g^2 forward (see Figs. 15 and 16,) 75 so that the end thereof engages the shuttle-thread 4 and draws out enough thread from the shuttle so that after the thread is severed there will be sufficient for the beginning of the stitch at the next operation. Just 80 as the pull-off has completed drawing out the thread the rock-shaft i will have caused the arm q^2 to draw the slide l^2 back far enough for the edge o^2 to coöperate with the blade k^2 in severing the upper thread 5. (See Figs. 8 85 and 9.) At this time the under thread 4 will not be cut, as it is resting against the edge p^2 of the blade n^2 . The rock-shaft i , continuing in its movement, causes the arm l' to rock the rock-shaft v^2 through the medium of the link x^2 and the arm w^2 . This causes the pull-off n^3 to be moved down through the guides k^3 , the friction-disk i^3 having been just thrown into the position shown in Fig. 13 to allow the thread to slip easily 95 by for this purpose; and practically simultaneously therewith the roller d^2 on the arm c^2 strikes the arm b^2 of the toggle-lever z' and allows the pin v' to rise. The spring r' in rocking the lever p' swings the kicker s' on its pivot through the medium of the rigid link u' , so that the finger t' engages the upper thread and draws the severed end thereof out of the fabric for the beginning of a stitch at the next operation. At the same time or 100 at a period of time slightly thereafter the arm q^2 draws the plate far enough to the rear for the edge p^2 of the blade n^2 , with the aid of the blade k^2 , to shear or sever the under thread 4, as shown in Fig. 10. By this time 110 the upper clamp q' has been raised by the lever p' , so that the work may now be taken from the machine.

The parts have to be all accurately timed and correlated in order that they may perform 115 their functions at precisely the proper time and in the proper sequence. As the cam a' completes its revolution for the final movements of the parts which cause the severing of the thread the end of the bar t enters the 120 notch h' in the cam a' and locks the needle-bar in its raised position, as well as locking all the other operative parts of the machine, with the exception of the continuously-moving driving-shaft, the gear-wheels, and the 125 cam m . The adjustment of the cam a' relatively to the fixed pulley c' permits of the parts being timed a little differently relatively to the movements of the needle-bar-driving shaft f , and the cushioning devices inserted between the cam a' and the fixed pulley c' provide against any injurious shock to the machine by the sudden stopping of the cam a' in its revolution.

When the operator places new work between the clamps o' and q' , the key or push-button r is pressed down to move the roller l' on the lever k laterally into engagement with the continuously-operating cam m . As the cam revolves it rocks the lever down to its lowest position, and as the rock-shaft is thus being rocked down the rock-shaft v^2 is first actuated by the weight of the link x^2 to allow the friction-disk i^2 to slide back into engagement with the thread and the upper thread pull-off n^3 and the locking or wedging lever a^3 to assume their non-operative positions, as illustrated in Fig. 3. Thus the upper thread is freed for the stitching, and the pull-off n^3 and the locking-lever a^3 are locked back out of the way. The next effect of the movement of the rock-shaft is to move the lever q^2 and the sliding knife-blade back out of the way of the needle to their non-operative positions. Simultaneously therewith the arm c^2 is rocked down so as to swing the under thread pull-off g^2 back out of the way, so as to release the under thread. As the end of the lever c^2 descends the roller d^2 strikes against the arm a^2 of the toggle-lever z' , which throws the toggle-levers into their locked position and draws down the pin r' . As the pin is drawn down it draws with it the horizontal arm of the lever p' , so as to bring the upper clamp q' down firmly against the work. The movement of the lever p' likewise draws the kicker s' and the finger t' back away from the needle. Then as the rock-shaft and the arm l' thereon reach the lowest limits of their movements the toggle-levers $m' m'$ slip into their locked position. In doing this the said levers positively lock the rock-shaft i against movement, and thereby prevent any movement whatsoever of all of the operative parts of the machine except those which are actuated by the fast pulley c' or the needle-bar-driving shaft.

It will be understood that all the operations of the different parts which are effected by the rock-shaft i occur while the needle-bar-driving shaft f is making one revolution and the needle is moving down and up once. There is practically but small movement of the rock-shaft i from the time when the end of the bar t moves into engagement with the cam until the latter has nearly completed its revolution—that is to say, the rock-shaft receives its first positive movement when the end of the bar t passes down the shoulder from the dwell 2 to the dwell 1, the dwell 1 being eccentric to the axis of the shaft f , so that practically the greater part of the movements of the operative devices occur during the last quarter of the revolution of the cam a' .

Having thus explained the nature of the invention and described a way of constructing and using the same, although without having attempted to set forth all of the forms in which it may be made or all of the modes of its use, I declare that what I claim is—

1. In a sewing-machine, stitch-forming devices, comprising an upper-thread mechanism, and an under-thread mechanism, a stationary blade, a movable blade, said blades being located under the work, and being adapted to cut both the upper and the under threads, and means for automatically actuating said movable blade to cut said threads immediately upon the completion of a stitching operation, whereby said work may be removed from the machine. 70

2. In combination with a two-thread sewing-machine, a stationary blade located below the work, a movable blade having two cutting edges, (one for the upper thread and the other for the under thread,) and means for actuating the movable blade. 80

3. In a sewing-machine, stitch-forming devices comprising upper-thread mechanism and under-thread mechanism, a cutting device for severing the under thread, and means for drawing out the under thread to leave an end of sufficient length for the next stitch. 85

4. In a sewing-machine, an upper-thread mechanism, an under-thread mechanism, a cutting device for severing the under thread, and a pivoted pull-off for drawing out the under thread whereby it will be sufficiently long for the next stitch. 90

5. In a sewing-machine, an upper-thread mechanism and under-thread mechanism, a cutting device for severing the under thread, a pull-off for the under thread, and means for actuating the cutting device and the pull-off. 95

6. In a sewing-machine, upper-thread mechanism, under-thread mechanism, a cutting device for severing the under thread, and a pull-off movable relatively to the cutting device for drawing out the under thread. 100

7. In a sewing-machine, upper-thread mechanism, under-thread mechanism, a cutting device for severing the under thread, and a pull-off independent of said cutting devices for drawing out said under thread to provide 110 a loose end of sufficient length for the next stitch.

8. A sewing-machine, comprising under-thread mechanism, a pull-off for drawing out the under thread, a cutting device for severing the thread, means for actuating both the pull-off and the cutting device, and means for locking the first said means to hold the said pull-off in an inoperative position. 115

9. A sewing-machine, comprising an under-thread mechanism, a pull-off for drawing out the thread, a cutting device for severing the under thread, means for actuating both the pull-off and the cutting device, and mechanism comprising toggle-levers for intermittently locking said means against movement. 120

10. In a sewing-machine, the combination with a stitch-forming mechanism, including an upper needle and its bar, of a device for severing the needle-thread located below the work, and an automatic device for engaging said thread between the needle-eye and the

work and drawing the severed end of said thread out of the work without moving said work.

11. In a sewing-machine, the combination with a stitch-forming mechanism, including an upper needle and its bar, of a device for severing the needle-thread, an automatic kicker for drawing the severed end of the thread out of the work, and means for maintaining said kicker inoperative during the operation of the stitch-forming mechanism.

12. In a sewing-machine, the combination with a stitch-forming mechanism, of a device located below the work for severing the thread, a kicker for drawing out the severed end of the thread, and means including toggle-levers for holding said kicker in a non-operative position.

13. In a sewing-machine, the combination with a stitch-forming mechanism, of a device located below the work for severing the needle-thread, a kicker for drawing out the severed end of the thread, means including toggle-levers for holding said kicker in a non-operative position, and an automatically-acting device for unlocking said toggle-levers.

14. In a sewing-machine, the combination of the lower clamp, a pivoted lever, an upper clamp secured thereto, a kicker for the thread pivoted to the standard, a link connecting the lever with the kicker, a spring for raising the lever up so as to move the upper clamp away from the lower clamp and the kicker into its operative position, and toggle-

levers for locking said lever down with the upper clamp against the lower clamp and the kicker in an inoperative position.

15. In a two-thread sewing-machine, the combination with a stitch-forming mechanism, of a cutting device for the threads, a lever for drawing out the under thread prior to its being severed, and means for varying the movements of the said device and the said lever.

16. A sewing-machine comprising a driving-shaft for the stitch-forming mechanism, a cutting device for severing the thread, a movable bar connected meditately with the said device for operating it; and a cam on the said shaft, against which the bar is adapted to press, said cam being adjustable relatively to said shaft.

17. A sewing-machine including a continuously-rotating shaft, a driving-shaft for the stitch-forming mechanism, belt-shifting mechanism, a device for cutting the thread, a device for drawing out the severed end of said thread, means for operating the belt-shifting mechanism and both said devices and mechanism including a hand-operated key for connecting said means with said continuously-rotating shaft.

In testimony whereof I have affixed my signature in presence of two witnesses.

GEORGE S. HILL.

Witnesses:

HENRY J. MILLER,
HARROLD W. BROWN.
